UNITED STATES PATENT OFFICE.

THEODORE R. TIMBY, OF NYACK, NEW YORK.

COOKING-VESSEL.

SPECIFICATION forming part of Letters Patent No. 224,492, dated February 10, 1880.

Application filed July 7, 1879.

To all whom it may concern:

Be it known that I, THEODORE R. TIMBY, of Nyack, Rockland county, New York, have invented certain new and useful Improvements in Cooking-Vessels, of which the following is a specification.

My invention applies to kettles, pots, boilers, sauce-pans, or other vessels of stove or culinary ware constructed with a pendent jacket surrounding the water-chamber, the lower edge of which rests upon the stove-top, and thus forms an annular heating-chamber around the water-chamber, into which the heat is radiated and reflected against the water-chamber. My improvement lies in a shield or lining to the lower portion of the said jacket, whereby the jacket is protected against the direct heat and its surface kept bright and cleanly, as hereinafter fully set forth.

In the drawing the figure presents a vertical central section of a kettle constructed with my improved lined jacket.

As illustrated, *a* indicates the water-chamber of the kettle, which is preferably of the form of an inverted truncated cone, its lower end being designed to be a loose fit for the stove-hole, so as to leave a marginal part of the said hole uncovered.

b indicates the jacket, which is preferably of cylindrical form, and depends from the upper part of the water-chamber, and terminates at a short distance above the tapering base thereof, as shown, so that the water-chamber is adapted to project into the stove-hole, while the jacket surrounds the said hole and supports the kettle over the same. It will now be seen that the jacket incloses an annular space around the water-chamber, into which the heat from the stove-hole is radiated, and being reflected and confined by the said jacket upon the water-chamber on all sides thereof, the heating effect is thus greatly increased.

Now, my improvement consists in providing the interior of the jacket with the shield or lining *c*, which encircles the interior of the jacket at its lower part, and is preferably isolated slightly therefrom, except at its lower edge, where it is turned over and fixed to the lower edge of the jacket, while from this point upward the shield preferably flares outward from the jacket, so as to form an insulating air-space between the two, as illustrated.

The shield or lining preferably extends about three-quarters the height of the jacket, as shown; but its relative height may be more or less without objection, and as thus constructed it of course forms an integral part of the jacket itself.

It will now be seen that the lower edge of the lining or shield rests upon the stove-top and protects the edge of the jacket or the outer part of the jacket from direct contact therewith. Furthermore, the heat from the stove-hole is radiated against the shield and thence thrown upon the water-chamber, thus effectually preventing the direct conduction or radiation of heat to the outer jacket, and hence preventing the same becoming so highly heated as to waste much of this heat by outward radiation, and at the same time preventing the outer jacket becoming quickly oxidized, thus enabling it to remain much longer in a bright condition, which is, of course, not only more pleasing in appearance, but is more favorable to the retention of heat and obviates frequent polishing. It will also be observed that the inward inclination of the lining or inner jacket toward the water-chamber renders the same a much more efficient heating-reflector, as it reflects the heat at a more favorable angle downward toward the base of the water-chamber, which is, of course, the most favorable direction, as heat is largely wasted when applied to the top of a liquid. Hence by this improvement a much better heating effect is obtained, while the outside of the vessel preserves its bright appearance much longer, which are important advantages in a culinary article.

The improved vessel may be made of any suitable metal; but I ordinarily prefer to form the water-chamber and jacket of copper and the shield of bright tin; but the entire vessel may be made of one metal and be cast or otherwise formed.

What I claim as my invention is—

A cooking-vessel constructed with a heat-confining jacket around its water-chamber, with a shield or lining, *c*, arranged at the lower part thereof, and adapted to protect the jacket from the direct heat, substantially as herein shown and described.

T. R. TIMBY.
